[73] Assignee: Sumitomo Wiring Systems, Ltd., Yokkaichi, Japan

[57] CLAIM

[*] Notice: The portion of the term of this patent subsequent to Jun. 23, 2006 has been disclaimed.

The ornamental design for an inner housing of an electrical connector, as shown and described.

[**] Term: 14 Years

DESCRIPTION

[21] Appl. No.: 271,470

FIG. 1 is a top perspective view of the inner housing of an electrical connector showing our new design. The broken line showing of the outer connector housing and the adjacent arrow are environmental elements included for illustrative purposes only and form no part of the claimed design:

[22] Filed: Nov. 15, 1988

FIG. 2 is a rear elevation view of the inner housing of an electrical connector showing our new design on an enlarged scale;

[30] Foreign Application Priority Data

FIG. 3 is a front elevation view thereof;

May 17, 1988 [JP] Japan 63-19367

FIG. 4 is a top plan view thereof;

[52] U.S. Cl. D13/147

FIG. 5 is a bottom plan view thereof;

[58] Field of Search D13/133, 146, 147;

FIG. 6 is a right side elevational view thereof, the left side elevational view being a mirror image;

439/353, 344, 357, 544, 550, 571, 572, 586, 587,

FIG. 7 is a cross-sectional view thereof taken along line 7—7 of FIG. 4;

595, 603, 660, 682, 685, 686, 687, 695, 696, 701

FIG. 8 is a cross-sectional view thereof taken along line 8—8 of FIG. 4; and,

[56] References Cited

FIG. 9 is a cross-sectional view thereof taken along line 9—9 of FIG. 4.
